(57) **CLAIM**

The ornamental design for a tray for feeding bottle sterilizer, as shown and described.

DESCRIPTION

FIG. 1 is a front perspective view of a tray for feeding bottle sterilizer;

FIG. 2 is a front view thereof where the back view is a mirror image;

FIG. 3 is a left view thereof where the right view is a mirror image;

FIG. 4 is a top view thereof;

FIG. 5 is a bottom view thereof; and,

FIG. 6 is a reference view showing the state of use in which the claimed design is inserted into a feeding bottle sterilizer. The broken lines in the drawings depict environmental subject matter and form no part of the claimed design.
